Primary Examiner — Eric L Goodman*(74) Attorney, Agent, or Firm* — Minder Law Group;
Willy H. Wong(57) **CLAIM**

The ornamental design for a bubble rocket, as shown and described.

DESCRIPTION

FIG. 1 is a front view of a bubble rocket showing the new design.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines in the Figures show portions of the bubble rocket that form no part of the claimed design.
